No. 880,352.

PATENTED FEB. 25, 1908.

C. S. BROADWELL.
LOOSE LEAF BINDER.
PUBLICATION FILED, AUG. 27, 19

APPLICATION FILED AUG. 27, 1907.

UNITED STATES PATENT OFFICE.

CHARLES S. BROADWELL, OF SANTA ROSA, CALIFORNIA.

LOOSE-LEAF BINDER.

No. 880,352.

Specification of Letters Patent.

Patented Feb. 25, 1908.

Application filed August 27, 1907. Serial No. 390,365.

To all whom it may concern:

Be it known that I, CHARLES S. BROADWELL, a citizen of the United States, residing at Santa Rosa, in the county of Sonoma and 5 State of California, have invented new and useful Improvements in Loose-Leaf Binders, of which the following is a specification.

This invention relates to loose leaf binders; and it has for its object to provide an improved device of this class having flexible 10 binder posts, constructed of wire rope and serving to connect the boards constituting the covers of the device in such a manner that the latter may be readily laid open for the inspection of any one of the leaves.

Further objects of the invention are to simplify and improve the construction and operation of this class of devices.

With these and other ends in view which 20 will readily appear as the nature of the invention is better understood, the same consists in the improved construction and novel arrangement and combination of parts which will be hereinafter fully described and particularly pointed out in the claims.

In the accompanying drawing has been 30 illustrated a simple and preferred form of the invention; it being, however, understood that no limitation is necessarily made to the precise structural details therein exhibited, but that changes, alterations and modifications within the scope of the invention may be resorted to when desired.

In the drawing, Figure 1 is a vertical transverse sectional view of a loose leaf binder constructed in accordance with the invention. Fig. 2 is a detail plan view showing one side of the cover open, for inspection, and part broken away for the purpose of exposing subjacent parts. Fig. 3 is a perspective detail view of the metallic back portion of the cover, detached. Fig. 4 is a side elevation, partly in section, of one of the binder posts. Fig. 5 is a perspective detail view of the engaging end of said post. Fig. 6 is a perspective detail view of the cap member used in connection therewith. Fig. 7 is a detail view in side elevation, partly in section, of one of the flexible binder posts and the extension member sometimes used in connection therewith. Fig. 8 is a perspective detail view illustrating a modified form of one of the extension members.

Corresponding parts in the several figures 5 are denoted by like characters of reference. The improved binder comprises the front

and rear cover boards 1-2 which may be made of wood, pasteboard or other suitable material, suitably covered with paper, textile fabric, leather or other suitable material or combination of materials. A rigid strip 3 of metal is hingedly connected with the back edge of the front cover board 1, the hinge connection being formed by the flexible material 4-4 with which the parts 60 are covered; a back member 5 is in like manner connected with the back edge of the rear cover board 2; said back member consisting of a curved or trough shaped strip of metal having a longitudinal flange 70 6 adjacent to the edge which is connected with the cover board; said curved or trough shaped strip being provided with reinforcing braces 7 the functions of which will be hereinafter fully set forth. Hingedly connected with the trough shaped member 5, along the free edge of the latter, is a rigid strip 8, preferably of metal, mating or corresponding with the strip 3 attached to the back edge of the front cover board. The 80 strip 8 is preferably connected with the trough shaped member 5 by means of flat metallic loops 9 engaging suitable slots 10 in the proximate edges of the connected parts which in this manner will be strongly and 85 efficiently connected; the covering material 4 is extended over the back member 5 and the strip 8 in such a manner as to present a neat finish.

The binder posts P of which any desired 90 number may be used although two are usually considered sufficient, are firmly secured upon the strip 3 adjacent to the front cover board from which they project in the direction of the rear cover board; the strip 95 8 being provided with apertures 11 for the passage of said posts. The bodies of the latter are composed of pieces 12 of wire cable or rope, possessing great strength and sufficient flexibility to enable them to bend or 100 yield in the act of laying open the binder for the inspection of leaves placed therein. The outer ends of the bodies of the posts are provided with metallic ferrules 13 suitably connected therewith and having sockets 14 105 which are internally threaded and provided with grooves 15 extending longitudinally through said sockets and disposed at diametrically opposite sides of the latter. The posts are provided with detachable caps 16, 110 exteriorly engaging the ferrules 13 and having screw threaded shanks 17 engaging

the threaded sockets and having diametrically opposite reduced or flat faces 18 enabling the said shanks, when the threaded portions thereof are placed in alinement 5 with the grooves 15 of the sockets to be slid or moved lengthwise in the latter to the desired position after which, by a quarter turn of the caps, the threaded portions of the shanks may be placed in engagement 10 with the threaded portions of the sockets, thus connecting the parts and assembling the same with sufficient security for all practical purposes. The caps have been shown as being of polygonal shape, and 15 provided with flat faces 19 to enable them to be grasped and turned by the thumb and finger of the operator, without the use of wrenches, keys or other tools.

It will be readily seen by the construction 20 described the extremities of the ferrules will engage or enter into the portions of the caps surrounding the shanks, thus presenting a neat finish; when the tips of the ferrules are entered into the caps nearly as far as they 25 will go, a quarter turn of the caps will secure the latter firmly upon the posts, this being practically the extent to which they may be moved; when the binder has been practically filled with loose sheets or leaves, to 30 such an extent that the shanks of the caps may only be partially entered into the sockets of the ferrules, the expansive pressure of the sheets or leaves will create a friction between the threaded portions of the shanks and the sockets which is found sufficient to retain the parts securely in position when assembled. The caps, the shanks of the latter, and the sockets of the ferrules may be made of any desired dimensions to 35 increase the capacity of the device to the desired extent. After the caps have been turned to engage the shanks with the threaded portions of the sockets, the trough-shaped strip 5 is turned over the caps, to the 40 position indicated in Fig. 1 of the drawings, when the transverse reinforcing braces 7 of said trough-shaped strip will engage the flat side faces of the caps which are thus held securely against turning; the braces 7 being properly located to coöperate with the caps in the manner indicated. The braces 45 7 will thus not only serve to reinforce the trough-shaped strip 5, but they constitute locking devices whereby the caps 16, when 50 accommodated in the trough-shaped strip, will be prevented from being accidentally turned or displaced, thus constituting a simple and efficient locking device.

For the purpose of facilitating the insertion 55 of additional leaves in the binder when the latter has been nearly filled, extension members are provided for use in connection with the binder posts, said extension members consisting of cylindrical rods 21 of a 60 diameter corresponding with that of the

posts and the ferrules from the ends of the latter; said rods being provided with screw threaded shanks 22 for engagement with the sockets of the ferrules, and with heads 23 of greater diameter than the apertures 11 in 70 the strip 8. The outer ends of the extension members may, if desired, be provided with sockets corresponding with the sockets 14 at the outer ends of the binder posts, and into which the screw threaded shanks 17 of the caps 16 may be inserted; this construction being illustrated in Fig. 8 of the drawings where the socket upon the end of the extension member is designated 14'.

In operation, the loose leaves or sheets are 80 perforated in the manner customary in this class of devices to enable them to be strung upon the posts P; after which the extremities of said posts are entered through the apertures 11 of the strip 8, and the caps or 85 extension members are then placed in position; loose leaves being suitably strung upon the extension members when the latter are used. The caps 16, or the heads of the extension members, as the case may be, are 90 accommodated within the trough shaped back member 5, and it will thus be seen that no metallic parts, screws, bolts, connecting members or the like are exteriorly exposed upon any portion of the binder. This is 95 regarded as a very important advantage for the reason that scratching or marring of the polished surfaces of tables, desks or counters upon which the binder may be placed for examination of the contents will thus be avoided. Loose leaf binders of ordinary construction, so far as I am aware, have always been 100 open to this objection, the metallic parts having been exposed to a greater or less extent; by the present invention this objection 105 is entirely overcome. It will also be observed that owing to the flexible nature of the binder posts, the device may be readily laid open for examination of any one of the leaves or sheets contained therein, in 110 such a manner that such leaf will be flatly exposed, and not bulged or curved as is usually the case; this is obviously extremely desirable; especially in cases where it is found necessary to write upon the leaves. 115 The construction moreover is such as to admit of the parts being readily disassembled for the removal of leaves, or the placing of new leaves at various points.

Having thus fully described the invention, 120 what is claimed as new is:—

1. A binding device comprising covers, a trough shaped back member flexibly connected with one of the covers, rigid strips flexibly connected respectively with the 125 trough shaped back member and with the back edge of the mating cover, flexible posts secured upon the strip attached to the back edge of the mating cover and adapted to engage apertures in the strip connected with 130

the trough shaped back member, and cap members detachably engaging the flexible posts.

2. In a binding device comprising covers, a trough-shaped back member flexibly connected with one of the covers, rigid strips flexibly connected respectively with the trough-shaped back member and with the back edge of the mating cover, binder posts secured upon the strip attached to the back edge of the mating cover and engaging apertures in the strip connected with the trough-shaped back member, cap members detachably engaging the binder posts, and cap engaging locking means connected with the trough-shaped back member.

3. A binding device comprising covers, a trough-shaped back member flexibly connected with one of the covers, rigid strips flexibly connected respectively with the trough-shaped back member and with the back edge of the mating cover, binder posts secured upon the strip attached to the back edge of the mating cover and engaging apertures in the strip connected with the trough-shaped back member, polygonal cap members detachably engaging the binder posts and transverse braces secured in the trough-shaped back member and adapted for engagement with the side faces of the polygonal cap members.

4. In a loose leaf binder a pair of cover members, binder posts connected permanently with one of the cover members and extending through apertures in the other cover member, cap members upon the projecting ends of the binder posts, a trough-shaped back member connected with one of the cover members and adapted to be folded over the cap members at the projecting ends of the binding posts, and means connected with said trough-shaped back member for locking the cap members. 35 40

5. A binding device comprising a front cover, a rigid strip flexibly connected therewith, a rear cover, a trough-shaped back member flexibly connected therewith, a rigid strip flexibly connected with the trough-shaped back member and having apertures, flexible posts secured upon the strip connected with the front cover and having socketed ferrules engaging the apertures in the strip connected with the trough-shaped back member and cap members having shanks detachably engaging the 50 55 socketed ferrules.

In testimony whereof I affix my signature in presence of two witnesses.

CHARLES S. BROADWELL.
